CLAIM

The ornamental design for an adaptable, disposable grass catching bag for a lawn mower, as shown and described.

DESCRIPTION

FIG. 1 is an isometric view of an adaptable, disposable grass catching bag for a lawn mower showing my new design;

FIG. 2 is a front view thereof;

FIG. 3 is a rear view thereof;

FIG. 4 is a left-hand side view thereof;

FIG. 5 is a right-hand side view thereof;

FIG. 6 is a top view thereof; and,

FIG. 7 is bottom view thereof.

1 Claim, 6 Drawing Sheets
